(57) **CLAIM**

The ornamental design for a ramp skid plate, as shown and described.

DESCRIPTION

FIG. 1 is a perspective view of a ramp skid plate showing my new design;

FIG. 2 is a magnified sectional view of the area marked in FIG. 1;

FIG. 3 is a top plan view thereof;

FIG. 4 is a rear top plan view thereof;

FIG. 5 is a right side elevation view thereof;

FIG. 6 is a left side elevation view thereof;

FIG. 7 is an end view thereof;

FIG. 8 is the other end view thereof;

FIG. 9 is a rear perspective view thereof; and,

FIG. 10 is a magnified sectional view of the area marked in FIG. 9.

The broken lines in the figures define the bounds of the claimed design and form no part of the claimed design.
